UNITED STATES PATENT OFFICE

136,214

DESIGN FOR A COMBINED PENCIL, SAND-GLASS TIMER, AND TELEPHONE DIALER

Ernest C. Collopy and Carl J. Collopy,
New Bedford, Mass.

Application March 20, 1943, Serial No. 109,783

Term of patent 14 years

To all whom it may concern:

Be it known that we, Ernest C. Collopy and Carl J. Collopy, citizens of the United States and residents of New Bedford, county of Bristol, and State of Massachusetts, have invented a new, original, and ornamental Design for a Combined Pencil, Sandglass Timer, and Telephone Dialer, of which the following is a specification, reference being made to the accompanying drawing, forming part thereof.

In the drawing showing our new design:

Figure 1 is a side elevation of a combined pencil, sandglass timer, and telephone dialer embodying our new design.

Figure 2 is a section on line 2—2 of Fig. 1.

Figure 3 is a side view partly in section of the instrument shown in Fig. 1.

What we claim is:

The ornamental design for a combined pencil, sandglass timer, and telephone dialer as shown.

ERNEST C. COLLOPY.
CARL J. COLLOPY.
